DEVICE FOR DRESSING GRINDING WHEELS
AND THE LIKEJohn Y. Blazek, Bedford, Ohio, assignor to
Lempeo Products, Inc., Bedford, Ohio, a corpora-
tion of Ohio

Application May 22, 1943, Serial No. 488,020

7 Claims. (Cl. 125—11)

This invention relates, as indicated, to devices for dressing grinding wheels and the like.

A primary object of the invention is to provide a device for dressing grinding wheels in which means are provided for clamping the device to the work to be ground, and for aligning the dressing tool and grinding wheel with the work to be ground.

Another object of the invention is to provide a device of the character described having a dressing tool holder mounted for movement enabling radii to be ground on a grinding wheel, and having means incorporated therein for limiting the movement of the holder beyond predetermined positions during such grinding.

A further object of the invention is to provide a device of the character described having novel means for clamping the dressing tool holder in a fixed position to enable the face of a grinding wheel to be dressed.

Other objects and advantages of the invention will be apparent during the course of the following description.

In the accompanying drawings, forming a part of this specification, and in which like numerals are employed to designate like parts throughout the same.

Fig. 1 is a view, partly in elevation, and partly in section, of a device embodying the invention;

Fig. 2 is a fragmentary elevational view of a portion of the device, as viewed in the direction indicated by the line 2—2 of Fig. 1;

Fig. 3 is a cross-sectional view, taken on the line 3—3 of Fig. 2;

Fig. 4 is a fragmentary cross-sectional view, taken on the line 4—4 of Fig. 1;

Fig. 5 is a fragmentary cross-sectional view, taken on the line 5—5 of Fig. 1;

Fig. 6 is a view, illustrating the use of the device for truing or dressing the peripheral surface of a grinding wheel;

Fig. 7 is a view, similar to Fig. 6, but illustrating the use of the device for grinding a radius on a grinding wheel;

Fig. 8 is a plan view of the body of a locating gauge which is used to determine the radius which is to be ground on a grinding wheel, and

Fig. 9 is a side elevation of the gauge assembly.

Referring more particularly to the drawings, it will be seen that the device comprises a supporting bar 1 having secured to and extending laterally from the upper end thereof a bracket 2, the bracket being secured to the bar 1 by means of socket head cap screws 3.

The bracket 2 has a bearing 4 disposed therein adjacent its outer end, this bearing being secured in position by means of a socket head set screw 5 having a dog point.

5 The bearing 4 has a conical surface 6 which forms a seat for the conical intermediate portion 7 of a driving pin, the upper portion 8 of which extends through the bracket 2, and has secured thereto a crank handle 9, and the lower portion 10 of which is secured, as by means of a taper pin 11, to a dressing tool holder 12.

The supporting bar 1 has secured to and extending laterally from the lower end thereof, a bracket 13, this bracket being secured to the bar 15 by means of socket head cap screws 14.

The bracket 13 has threadedly secured therein, in alignment with the driving pin 7—8—10, a slotted head set screw 15 having a dog point 16 which serves as a thrust bearing for the lower end of the tool holder 12, the point 16 being seated in a seat element 17, secured in position by means of a socket head set screw 18 having a dog point engaging this element. The set screw 15 may be adjusted to take up wear between the point 16 thereof and the seat element 17, and is locked in adjusted position by means of a lock-nut 19.

It will be noted that the brackets 2 and 13 are curved to conform with the curved ends of the tool holder 12, and that the tool holder has secured therein, at a point substantially midway of its ends, a diamond-pointed dressing tool 20, which may be adjusted axially and locked in adjusted position by means of a socket head set screw 21 having a cone point engaging the tool.

For the purpose of locking the tool holder 12 to the bar 1, as when grinding a flat face on a grinding wheel, in a manner to be presently described, a set screw 22 is provided, having a cone point 23 at one end, and a knurled collar 24 secured to the head thereof, the screw being threadedly mounted in the holder 12. When the holder 12 is to be locked to the bar 1, the screw 27 is rotated so as to cause the cone point 23 thereof to extend into a V-shaped recess 25 in the adjacent face of the bar 1.

The device further includes a work gripping clamp 26 which is coplanar with the bar 1 and brackets 2 and 13, and which may be vertically adjusted relatively to the bar 1. For this purpose, the clamp is recessed at its edge 27 to fit a guideway or tenon 28 which projects from the bar 1, this tenon thus serving to maintain the clamp 26 coplanar with the bar in all adjusted positions. The clamp is secured to the bar 1

by means of socket head cap screws 29, the heads of which are disposed in recesses 30 in the bar 1 and the stems of which extend through slots 31 in the bar 1 and into the clamp 26. To adjust the clamp 26, all that is necessary is to loosen the screws 29, move the clamp upwardly or downwardly, and then tighten these screws.

The clamp 26 is provided with a V-seat 32 for the work to be ground, and with a cooperating clamping element 33 which is threadedly secured to the clamp 26 and is provided with a handle 34 for manipulating the clamping element.

A small level 35, whose function will be presently described, is mounted on the upper edge 36 of the clamp, and is secured to such edge by means of clips 37.

The device further includes a scale 38 which is secured to one side of the bar 1, and the purpose of which will also be presently described.

Having thus described the general constructional features of the device, the two principal uses thereof will now be described.

The first of these uses involves the dressing or truing of the peripheral face F, of a grinding wheel GW, which, for example, is to be used to grind a crankshaft C, it being assumed that in the grinding machine on which the crankshaft is mounted to be ground, that the wheel GW is movable away from the crankshaft sufficiently to permit the dressing device to be attached to the crankshaft in the manner shown in Fig. 1.

If the crankshaft is four inches in diameter, the clamp 26 is first adjusted so as to bring the index line 39 thereof in alignment with the 4 inch mark on the scale 38, after which the clamp is securely fastened to the bar 1 by means of the screws 29. The clamp 26 is then secured to the crankshaft, by causing the crankshaft to seat in the V-seat 32, and bringing the clamping element 33 into engagement with the crankshaft, the entire device being first adjusted, however, to insure that the level 35 indicates that bar 1 is vertical.

The holder 12 is then locked to the bar 1 in the manner hereinbefore described, so that the point of the dressing tool 20 is in horizontal alignment with the center of the crankshaft, as well as the center of the wheel GW.

With the parts thus positioned, the wheel GW is brought into engagement with the tool 20, and is moved axially by any suitable traversing means, so as to cause the tool 20 to grind or dress the peripheral face F of the wheel, as diagrammatically indicated in Fig. 6, it being understood that the grinding wheel is rotated at a suitable speed during this dressing operation.

After the wheel has been properly dressed, the dressing device is removed, so as to permit the grinding wheel to be brought into operative grinding relation to the crankshaft C, which is to be ground.

The other use of the device involves the grinding or dressing of a radius on the peripheral face of the grinding wheel.

For this purpose, the device is set up and adjusted as previously, but the radius to be ground is first determined by means of a locating gauge such as shown in Figs. 8 and 9, said gauge comprising a round bar 40 having a flattened surface 41 to which is secured a scale 42, along which a tool locating element 43 may be adjusted to any desired position, and locked in adjusted position by means of a set screw 44. The hardened end 45 of the bar 40 is first brought into engagement

with a hardened steel insert 46 in the bar 12. The element 43 of the gauge is then set at a position on the scale which represents the radius to which the wheel is to be dressed, after which the dressing tool 20 is adjusted in the tool holder 12 so as to bring the diamond point thereof into engagement with the face 47 of the element 43, so that the tool 20 is now set to produce the desired radius on the wheel.

10 The set screw 27 is then withdrawn from the recess 25 in the bar 1, so as to permit the tool holder 12 to be rotated about its pivotal axis.

The grinding wheel GW is then brought into engagement with the diamond point 20, and the 15 wheel is rotated as the holder 12 is rotated about its pivotal axis by means of the handle 9, so as to grind a radius R on the face of the grinding wheel, as shown in Fig. 7.

In order to insure the diamond point from passing the diametral plane D—D of the grinding wheel, when a radius is to be ground on only one side of this plane, the bracket 2 is provided with a thumb screw 48 at each side thereof, which thumb screw, when moved into the path of the 25 holder 12, prevents the holder from moving beyond the plane in which it is shown in Fig. 1.

Movement of the holder in the opposite direction is limited by one of the stops 49, which depend from the bracket 2, and have flat surfaces 30 50 against which the holder 12 impinges to prevent the diamond point from biting into the grinding wheel, which would occur if the tool were permitted to move beyond the extremity of the radius which is to be ground.

35 After the radius has been ground, the device is removed, so as to permit the wheel to be brought into operative engagement with the work to be ground.

It is to be understood that the form of my invention, herewith shown and described, is to be taken as a preferred example of the same, and that various changes in the shape, size and arrangement of parts may be resorted to, without departing from the spirit of my invention, or the 45 scope of the subjoined claims.

Having thus described my invention, I claim:

1. In a device of the character described, a supporting bar, a clamp secured to said bar and adjustable therealong, said clamp adapted to be clamped to work to be ground, and a dressing tool holder pivotally mounted on said supporting bar.

2. In a device of the character described, a supporting bar, a clamp secured to said bar and adjustable therealong, said clamp adapted to be clamped to work to be ground, a dressing tool holder pivotally mounted on said supporting bar, and means on said clamp for indicating a level position of the clamp when clamped to said work.

3. In a device of the character described, a supporting bar, work clamping means secured to said bar and movable therealong, and a dressing tool holder pivotally mounted on said supporting bar.

4. In a device of the character described, a supporting bar, means secured to said bar and adapted to be clamped to work to be ground, said means being adjustable along said bar, and a dressing tool holder mounted on said bar.

5. In a device of the character described, a supporting bar, means independent of and secured to said bar and adapted to be clamped to work to be ground, and a dressing tool holder pivotally mounted on said bar, said holder being independent of said bar.

6. In a device of the character described, a supporting bar, work clamping means comprising

a work-receiving bar secured to said supporting bar and adjustable longitudinally of said supporting bar, said work-receiving bar having a work-receiving seat therein, and a work engaging element threadedly mounted in said work-receiving bar opposite said seat and adapted to cooperate with said work-receiving bar in clamping the work to said work-receiving bar, said element being adjustable relatively to said work-receiving bar, whereby to adapt said work-clamping means for 10 clamping work of substantially different diameters, and means associated with said bars for

determining the position of one bar relatively to the other for work of different diameters to be clamped by said work-clamping means.

5 7. A device, as defined in claim 6, in which said last-named means comprises a scale on one of said bars and an index line on the other, said scale and line cooperating to indicate the position of the bars relatively to each other for work of different diameters to be clamped by said work-clamping means.

JOHN Y. BLAZEK.
